UNITED STATES PATENT OFFICE.

ARTHUR HOGAN ROCHFORT, OF POINT REYES, CALIFORNIA.

PROTECTIVE COVERING FOR VEHICLE-WHEELS.

SPECIFICATION forming part of Letters Patent No. 791,502, dated June 6, 1905.

Application filed November 3, 1904. Serial No. 231,252.

To all whom it may concern:

Be it known that I, ARTHUR HOGAN ROCHFORT, a citizen of the United States of America, residing at Point Reyes, county of Marin, 5 and State of California, have invented certain new and useful Improvements in Protective Coverings for Vehicle-Wheels; and I hereby declare the following to be a full, clear, and exact description of the same, reference being 10 had to the accompanying drawings, forming a part of this specification.

This invention relates to an improved covering or shield to protect vehicle-wheels from abrasive wear, especially wheels of the 15 resilient type—such as are employed for automobiles, bicycles, and the like—as described in the following specification and illustrated by drawings that form a part thereof.

My improvement consists in a reversible 20 overtire or shield composed of a reticulated web having its warp composed of numerous twisted strands of fine metallic wire laid about an elastic fibrous core and a woof of the same nature and material woven in a peculiar manner, commonly called "twill," whereby the 25 warp alone is exposed to wear and the woof protected from abrasion, the whole forming a construction whereby is attained certain qualities and functions that give operative endurance 30 not hitherto accomplished by such shields or coverings.

The object of my invention is to provide a 35 covering or shield for resilient wheels that will be flexible, elastic, non-corrosive, reversible, and as near as possible without inherent sliding action of the members one upon the other, which action with abrasive wear on the surface limits the endurance of such devices.

40 To accomplish these ends, I provide protective coverings for vehicle-wheels as illustrated in the drawings.

Figure I is a flat view of a section of my 45 improved covering or shield; Fig. II, an edge view of the same, and Fig. III a transverse section through the rim of a pneumatic wheel with my improved covering applied thereto.

The adaptation to the desired end and the 50 endurance of reticulated coverings for resilient vehicle-wheels have both been limited be-

cause of either external abrasive wear or internal wear by the members sliding one upon the other, either result soon destroying the integrity of the structure. The qualities of 55 flexibility and endurance of such coverings are determined by certain mechanical laws or rules on which my invention is predicated—namely, first, that flexure without crystallization or rupture is best attained by subdivision of the bending member, and hence I 60 provide for the warp of my reticulated covering of the width shown a thousand or more strands of twisted wires, as indicated in the drawing Fig. I; second, endurance of abrasive wear is attained by the independent stability 65 of the strands composing the warp and woof, so that if a part is worn away the remainder will continue to perform the required function and be held by the manner of their reticulation; third, in any reticulated web in 70 which both the warp and woof are exposed to wear the latter is soon destroyed because disposed transverse to the tractive force and to sliding action on the ground. This is the theory on which my improvement is based 75 and produces a protective covering, as shown in the drawings, now to be described.

The warp 1 being composed of twisted 80 strands of non-corrosive wire sufficient in number to produce the desired width, each warp-strand 1 is composed of six minor strands twisted about a fibrous core. Each minor strand is also composed of six twisted wires, so that each strand 1 contains thirty-six wires, and a web, as shown in Fig. I, with fifty 85 strands 1, composing the warp, contains eighteen hundred separate wires. The border or major strands 2 are made in a similar manner, with a fibrous core 3, and have each thirty-six wires, preferably of a larger size, because 90 not exposed to so much flexure as the body or convex face 4.

The manner of weaving or reticulation is 95 technically known as "twill." (Indicated in Fig. II.) The woof-strands 5, also consisting of thirty-six wires, are double—that is, two strands cross at each intersection and are wound about the major strands 2 at each side, by means of which latter the covering is held in place on the wheel-rim 7. In this manner 100

it will be seen that the transverse woof-strands 5 are not exposed to wear, and the warp-strands 1 being twisted and held at each crossing or intersection can be quite worn away without destroying the action and purpose of the covering. It will be understood that the number of strands and of wires in each strand can be varied to suit the diameter of wheels, the nature of roads where the wheels are used, and that other subordinate structural changes may be necessary or advisable, the general features of my invention remaining the same.

In Fig. III, I show a manner of attaching the covering by means of clips 8, connecting to a ring or wire 9, disposed around and below the extreme diameter of the wheel-rim 7. This ring or wire is at this point rigidly held by expansion of the elastic rim when pressure falls on the face at 4 or at the time when the protective covering has to be held firmly in place. When one side of the protective covering is worn, the rivets 10 are taken out, the clips 8 removed, and the covering is reversed or the worn side turned inward against the wheel-tire 7, so there will be a new face with an endurance much the same as in the first use.

Having thus described the nature and objects of my invention and manner of its use, what I claim as new, and desire to secure by Letters Patent, is—

1. In resilient vehicle-wheels, a protective covering consisting of reticulated web, twill-

woven, the warp alone exposed to wear, the 35 warp-strands composed of multiple twisted wires disposed and operating in the manner substantially as described.

2. In resilient vehicle-wheels, a protective covering consisting of a reticulated web, twill-woven to expose the warp alone, the warp and woof composed of multiple strands of metallic wire, the woof double and passing over border or major strands at each side of the web, substantially as specified. 40 45

3. In a silent vehicle-wheel, a reversible protective covering, consisting of a reticulated web, woven to protect the woof, the strands composed of multiple twisted wires wound about a fibrous core and means to removably 50 attach the covering to the resilient tire of a vehicle-wheel, substantially as specified. 50

4. In a resilient vehicle-wheel, a protective covering composed of a reticulated web disposed in twisted strands of multiple wires, a 55 major strand at each side of the web around which the woof passes, and removable clips or other suitable fastenings that permit the covering to be reversed when worn on one side, substantially as specified. 60

In testimony whereof I have signed my name to this specification in the presence of two subscribing witnesses.

ARTHUR HOGAN ROCHFORT.
